PEDIATRIC URINE COLLECTOR

Edward J. Hill, 1660 Lochridge, Bloomfield Hills, Mich.

Filed Apr. 16, 1964, Ser. No. 79,532

Term of patent 14 years

(Cl. D83—1)

FIG. 1

FIG. 2

FIG. 3

FIG. 5

FIG. 1 is a side elevational view of a pediatric urine collector embodying my new design; and

FIG. 2 is a top view; and

FIG. 3 is a bottom view; and

FIG. 4 is a front elevational view; and

FIG. 5 is a rear elevational view thereof.

I claim:

The ornamental design of a pediatric urine collector, substantially as shown.
